UNITED STATES PATENT OFFICE.

GEORGE A. BARNARD, OF HARTFORD, CONNECTICUT.

STEAM-HEATING APPARATUS.

SPECIFICATION forming part of Letters Patent No. 429,182, dated June 3, 1890.

Application filed March 14, 1887. Serial No. 230,786. (No model.)

To all whom it may concern:

Be it known that I, GEORGE A. BARNARD, of Hartford, in the county of Hartford and State of Connecticut, have invented certain new and useful Improvements in Steam-Heating Apparatus, of which the following is a full, clear, and exact description, whereby any one skilled in the art can make and use the same.

10 The object of my invention is to provide an apparatus for heating by the circulation of steam in a suitable system of pipes and radiators, in which system the flow of the steam is caused or promoted by a device at 15 the end of the system of return-pipes.

To this end my invention consists in the combination, in a steam-heating apparatus, of supply-pipes, radiators, a return-pipe, and a suction device at the end of the return-pipe 20 operated by a flowing stream of steam through the ejector device, as more particularly hereinafter described, and pointed out in the claim.

Referring to the drawings, Figure 1 is a diagram view of a steam-heating apparatus as a whole, in which my within - described improvement is embodied, the suction device being shown at some distance from the locomotive-boiler for the purpose of making clear 25 the relative arrangement of the parts. Fig. 2 is a detail view, in vertical section, through the front part of a locomotive-engine, showing the cylinders and exhaust-pipes in section. Fig. 3 is a detail plan view of part of the connecting-pipes used in a locomotive with a 30 three-way valve cut in section.

In the accompanying drawings the letter *f* denotes the shell of a locomotive-boiler; *g* and *h*, the cylinders thereof; *g'* and *h'*, the exhaust-40 outlets from the cylinders, that are of ordinary construction and meet within the smoke-box or combustion-chamber just below the smoke-stack, as in the ordinary forms.

At suitable and convenient points in the 45 length of the exhaust-pipes *g'* and *h'* openings *i* are made, and in them or to them are connected the ends of the *Y* *j*' of the supply-pipes of a steam-heating system adapted to 50 conduct steam to the several cars making up a train.

The particular form and arrangement of the piping of the circulatory system used in the cars is not material to my improvement, it being requisite, however, that there should be no permanent opening in the return-pipe 55 *k*, that leads back to the engine through the shell and into the draft-chamber *k'* through an opening in the wall of the tube *k*², that surrounds the nozzles or discharge-outlet of the exhaust-pipes *g'* *h'*.

60 The operation of my device is as follows: The discharge of exhaust-steam from the cylinders through the exhaust-tubes into the tube *k*² causes an induced current through the drip or return pipe *k*, that draws upon the supply-pipes *j*, and causes a part of the exhaust-steam to pass through the opening *i* into the heating system of pipes.

Live steam may be utilized as the heating 65 medium by the following arrangement of parts: When the engine is not in operation, a connecting-pipe *m'* is provided leading from the boiler or steam-dome into the three-way cock *m*, that may be operated to provide the supply-pipes *j* with live steam, exhaust-steam, 70 when used, being supplied through the branch pipes *i* when the engine is in operation. The pipe *m'* may be provided with a suitable cock *m*², by means of which the live steam may be 75 shut off from the pipe *m'*, and the cock may 80 be located in position easily accessible from the cab of the locomotive. The supply-pipe *j* has connected to it, or is formed into suitable coils or heaters *j*', that are arranged in 85 convenient position in the cars. The return end of the last coil, or of a return-pipe common to all of the coils, is connected with the suction-return *k*, and also with a steam-trap *l* or suitable vale at the end of the returns, that is provided to automatically drain the pipes of any 90 surplus water of condensation that might otherwise accumulate in the end of the pipe. It will be understood that this steam-trap, whether it be in form of a **U**-syphon or **S**, has a seal sufficient to prevent the inflow of 95 air past the trap when the suction device is drawing on the system through the pipe *h*.

I claim as my invention—

In a locomotive - engine, in combination 100 with the cylinders having exhaust-pipes ter-

minating in a common nozzle, the supply-
pipe of a steam-heating system branching
from the said exhaust-pipes, and the return-
pipe of the said system opening into an an-
5 nular chamber formed about the nozzle of
the exhaust-pipes, whereby the outflow of the
exhaust-steam causes a draft through the re-

turn-pipe of the heating system, all substan-
tially as described.

GEORGE A. BARNARD.
